To all whom it may concern:

Be it known that I, FREDERICK MAX PORITZ, a German citizen, and a resident of the borough of Manhattan, city, county, and State of New York, have invented a new, original, and ornamental Design for a Lamp Base or Similar Article, of which the following is a specification, reference being had to the accompanying drawing, forming a part thereof.

Fig. 1 of said drawing is a plan view of a lamp base of my new design showing only a portion of the ornamentation of the base

Fig. 2 is a side elevational diagrammatic view of a lamp base of my new design showing the outline of the base member shown in Fig. 1.
